UNITED STATES PATENT OFFICE.

CARL O. FEDDERN, OF GERMANTOWN, PENNSYLVANIA, ASSIGNOR TO GLOBE TICKET COMPANY, OF PHILADELPHIA, PENNSYLVANIA, A CORPORATION OF PENNSYLVANIA.

TICKET-ISSUING MACHINE.

Application filed December 4, 1920. Serial No. 428,306.

To all whom it may concern:

Be it known that I, CARL O. FEDDERN, a citizen of the United States, residing at Germantown, Philadelphia, in the county of 5 Philadelphia and State of Pennsylvania, have invented new and useful Improvements in Ticket-Issuing Machines, of which the following is a specification.

My present invention relates to improvements in machines for issuing tickets, checks, or similar devices, and it pertains more especially to machines of this type capable of punching, or similarly marking, such tickets or checks with designations 15 which import a definite meaning to the ticket or check with reference to the intended use thereof.

The invention is particularly applicable to the issuance of tickets for use in connection 20 with the so-called zone system of fare collection as applied to the operation of electric or other railways, it providing a relatively simple machine capable of operating at relatively high speed to issue tickets rapidly, 25 such tickets being appropriately marked to indicate the zone, station, or other point at which it was issued, the ticket being surrendered by the passenger and the fare paid when the passenger leaves the car, the 30 amount of the fare to be paid being equal to the tariff charged between the point of issue of the ticket, as indicated thereon, and the point at which the passenger leaves the car.

The particular object of the present invention is to provide novel and improved means for punching or marking in an equivalent way, the tickets to indicate thereon the point of issue, each ticket having a number of spaces representing different points of 35 issue, the machine having a shifttable punch, or equivalent marking device, which may be quickly set and operated to punch or mark the appropriate point of issue upon the ticket. It is also an object of the invention 40 to provide means which will insure punching or marking of the ticket accurately within the appropriate point-of-issue-designating space thereof, the machine being capable of being restrained from operation unless it 45 is properly set. Punching or marking of the ticket partly in one space and partly in

another space thereof is thereby avoided.

To these and other ends, the invention consists in certain improvements and combinations and arrangements of parts, all as 55 will be hereinafter more fully described, the features of novelty being pointed out particularly in the claims at the end of the specification.

In the accompanying drawing—

Figure 1 represents a vertical section through a ticket issuing machine constructed in accordance with the preferred embodiment of the present invention;

Figure 2 represents a transverse section 65 through the machine looking toward the left in Figure 1;

Figure 3 is a detail view showing, on an enlarged scale, the marking device in the form of a punch, and the severing device in 70 the form of a knife;

Figure 4, represents, on an enlarged scale, a section taken horizontally through the machine showing the various mechanisms of the machine in top plan, excepting the 75 indicator;

Figure 5 is a detail section, on an enlarged scale, of the controlling means which restrains operation of the machine unless properly set and which limits the machine 80 at each operation, to the issuance of a single ticket.

Figure 6 is an exterior elevation of the upper portion of the front of the machine, showing one of the eight openings for the 85 indicator.

Figure 7 illustrates one form of a ticket or check adapted to be marked and issued by a machine as herein shown and described.

Similar parts are designated by the same 90 reference characters in the several views.

The invention in its present embodiment is herein shown as applied to a machine for issuing appropriately punched or marked tickets for use in connection with zone systems of fare collections on railways, and the machine in the present instance is similar in many respects to that shown and described in my application executed at even date herewith, the present invention particularly 100 relating to the means for punching or marking the tickets, the means for severing the

tickets from a ticket strip, and other features of construction and arrangement which will hereinafter appear. It is to be understood that the invention is not restricted to the precise construction and arrangement shown, as equivalent constructions and arrangements are contemplated and will be included within the scope of the claims.

In the present instance, the machine comprises a suitable frame 1 which serves to support the various elements or mechanisms of the machine, the frame, together with the elements supported thereby, being suitably enclosed by a casing 2. The ticket or tickets to be issued by the machine are preferably printed or otherwise prepared in the form of a strip 3 which contains a suitable number of tickets, and this strip is preferably wound into a roll 4 which is adapted to be fitted upon a sleeve 5 journaled on a shaft 6 secured to one side of the frame, preferably in the bottom thereof, the opposite end of this shaft being unattached relatively to the frame, in order to facilitate application of a fresh roll of tickets. In some instances, it may be preferable to fold the strip alternately in opposite directions, or in zigzag form to make a bundle, instead of forming the strip into a roll, and in such instances, the bundle of tickets may be placed in the bottom of the casing of the machine with the folds of the ticket strip superposed. In such instances, the roll supporting sleeve and shaft may be omitted. The ticket strip is advanced intermittently or by a step-by-step movement to bring the tickets successively into position to be punched or marked, severed and issued. Preferably, feeding means is employed for the ticket strip which will advance the same intermittently with precision so that each step of advance of the ticket strip is equal exactly to the length of the ticket on the strip, this insuring accurate registration of each ticket punching or marking means, and also the knife which severs the ticket from the strip. The ticket feeding means employed is also preferably of such a construction that during each step in the advance of the ticket strip, the ticket strip commences its movement slowly and with an accelerating speed until an intermediate stage in the advance of the ticket is reached, whereupon the speed of advance of the ticket strip diminishes and gradually ceases its movement as it approaches and reaches the end of its advancing movement, in order to avoid sudden movement or jerks upon the ticket strip which would give rise to difficulties in the feeding of the ticket strip. The feeding means shown in the present instance for accomplishing these results, comprises a main feed roll 7 which is fixed on a shaft 8, the latter being journaled at its ends in the opposite sides of the main frame, the main feed roll having a circum-

ference which is a multiple of the length of the ticket, the main feed roll has registering pins 9 which extend radially from its periphery, these pins being spaced circumferentially at intervals equal to the length of a ticket. The strip of tickets is provided with correspondingly spaced registering perforations 10, these perforations being preferably formed in the strip before the ticket strip is placed in the machine, as the perforating of the strip may be performed conveniently at the time the tickets are printed. The registering perforations in the ticket strip are preferably located adjacent to the dividing lines between adjacent tickets so that when the tickets are severed from the strip, these perforations will appear in an unused margin of the ticket, and hence they will not be confused with the marking perforations made in the ticket. The ticket strip is passed partially around the main feed roll 7, as shown in Figure 1, the registering pins 9 registering with and projecting through the corresponding perforations in the strip, the ticket strip being thus compelled to advance with the main feed roll to a degree which has a definite relation to the extent of advance of the feed roll. In order to insure the maintenance of proper engagement between the registering pins on the main feed roll and the perforations in the strip, a guard 11 is provided which has a surface which is concentric with the axis of the feed roll, this surface being arranged in close proximity to the periphery of the feed roll. The ticket strip passes through and is thus confined in the annular space between the periphery of the feed roll and the guard, and disengagement of the perforated portions of the ticket strip from the registering pins on the feed roll is prevented. The ticket strip passes tangentially from the periphery of the main feed roll to a slot 12 in the casing, through which the ticket is issued, a chute or shelf 13 being provided on the exterior of the casing, if desired, to form a support upon which the issued ticket is delivered. In order to assist the main feed roll 7 in feeding the ticket strip, a cooperative feed roll 14 is preferably provided which has a periphery which is grooved as at 15 to straddle the registering pins on the main feed roll, the portions of the periphery of the cooperating feed roll at opposite sides of the groove bearing on the outer side of the ticket strip. This cooperative feed roll is driven at the same peripheral speed as that of the main feed roll, in order that the ticket strip, which passes between these feed rolls, may be advanced easily and with certainty. As shown, the cooperative feed roll 14 is fixed on a shaft 15', the ends of which are suitably journaled in the opposite sides of the main frame, this shaft having a pinion 16 fixed thereon which

cooperates with a gear 17, the latter being fixed to the shaft 8 of the main feed roll 7. The gears 16 and 17 have a gear ratio which is appropriate to the ratio between the diameters of the feed rolls, and hence rotation of the main feed roll 7 will cause concurrent rotation of the cooperative feed roll at the same peripheral speed as that of the main feed roll.

- 10 The main feed roll 7 is rotated to advance the ticket strip the length of a ticket at each operation by means which comprises, in the first instance, a Geneva movement which includes a toothed wheel 18 which is fixed on the shaft 19 journaled in suitable bearings in the opposite sides of the main frame, this toothed wheel having tooth spaces 20 which have a definite relation to the registering pins 9 on the main feed roll, the shaft 19 for the toothed wheel 18 being connected to the shaft 8 of the main feed roll, by gears 21 and 22 of appropriate ratio, whereby each step in the rotation of the wheel 18, corresponding to the advance between adjacent tooth spaces thereon, will cause angular rotation of the main feed roll 7 which is equal to the angular spacing of adjacent registering pins thereon. The Geneva movement also comprises an actuator which embodies an arm 23 which is fixed on a shaft 24, this arm having a pin 25 which is arranged to operate successively in the tooth spaces 20 of the wheel 18, and the actuator also embodies a disk 26 which is also fixed on the shaft 24 and has a concentric portion on its periphery adapted to fit and revolve within arcuate portions 27 which are formed in the periphery of the wheel 18 in the intervals between the tooth spaces 20 therein, these arcuate portions being concentric with the shaft 24. The disk 26 also has a cut-away portion 28 in its periphery which clears the wheel 18 while the actuating pin 25 is operating in one of the tooth spaces of the wheel 18. At other times, the concentric portion of the disk 26 fits into an arcuate portion 27 of the toothed wheel 18, and thus locks the latter and also the main feed roll 7 from movement in either direction. In Figure 1, the actuator arm 23 of the Geneva movement revolves in an anti-clockwise direction, the pin 25 on its arm first entering one of the tooth spaces in the wheel 18 by a movement which is substantially radial to the shaft 19, but this actuating pin 25 moves in an arc which is concentric with the shaft 24, and hence continued movement of the pin 25, after it has engaged one of the tooth spaces 20 of the wheel 18, will cause the wheel 18 to rotate in a clock-wise direction (Figure 1), with a movement which accelerates as the pin moves further into the tooth spaces, although the rate of rotation of the shaft 24 may be constant or substantially so. This accelerating movement in the rotation of the

wheel 18 reaches its maximum midway in the advance of the wheel 18 and the main feed roll 7 driven by it, and as the shaft 24 continues to rotate in the same direction, the rate of movement of the wheel 18 diminishes gradually until the pin 25 passes out of the tooth space, at which time, the wheel 18 will be at rest, whereupon the concentric portion of the disk 26 engages the adjacent arcuate portion 27 of the wheel 18, thus locking the latter and also the main feed roll 7 from movement in either direction. The actuator arm 23 makes one complete revolution at each operation of the machine and during the advance of the toothed wheel 18 in a clockwise direction, the main feed roll 7 is advanced in an anti-clockwise direction, the ticket strip being thus advanced one ticket length at each operation of the Geneva movement. The shaft 24 which actuates the Geneva movement may be driven in different ways. In the present instance, it is driven from a longitudinally operating shaft 29 which is mounted in suitable bearings at opposite ends of the main frame through spiral gearing 30. This operating shaft 29 is provided exteriorly of the casing with a suitable manipulating part or handle, preferably in the form of a crank 31, each single revolution of which operates to perform the various steps of the cycle of operations of issuing an appropriately marked ticket.

The marking device is preferably in the form of a punch, which, according to the present invention, is shiftable relatively to the ticket to bring it into position to punch any one of the selected spaces or portions of the ticket intended to receive a designating mark. In the present instance, the ticket, as will appear from Figure 5 is provided with a row of spaces A, these spaces being arranged longitudinally on each ticket, and the punching device is shifting longitudinally of the ticket strip so as to bring the punch into register with any one of these spaces that may be selected for the purpose of indicating the point of issue of the ticket. Preferably, and as shown, the punch comprises a die 32 upon which the edge of the ticket strip, which is provided with the spaces, rests, and a punch 33 which normally occupies a retracted position above the plane of the ticket. Preferably and as shown, the punch is located in the space between the feed rollers and the wall of the casing through which the tickets are issued, and in order to properly support and guide the ticket strip between these points, a guide plate 34 having upper and lower members is mounted, the edge of the ticket opposite to the edge having the spaces thereon moving through the guide plate, whereby the ticket strip is supported in proper position to cooperate with the punching device. The die 32 is preferably formed as a part of a

130

body 35, and the punch 33 is preferably guided to reciprocate in this body in a direction transversely of the plane of the ticket. A spring 36 serves to retract the 5 punch and normally retain it in retracted position, and a collar 37 on the upper end of the punch is arranged to cooperate with a top plate 38 on the body 35, whereby the retracting movement of the punch is limited. 10 A stem 39 on the punch projects above the top plate 38 and serves to actuate the punch. The body 35 which carries the punch and its cooperating die is mounted to slide on a bar 40, the latter being fixed at its ends in 15 brackets 40^a and 40^b, this bar extending longitudinally of the portion of the ticket strip which spans the spaces between the feed rollers and the wall of the casing through which the tickets are issued. The 20 body 35 is slidable or shiftable longitudinally on this bar 40 so that the punch may be brought into register with any one of the longitudinally spaced portions of the ticket. Means is provided for shifting this body 35 25 together with the punch and its cooperating die along the bar 40 and for also retaining it in any position to which it may be shifted. Preferably, and as shown, such means comprises a screw 41 which is formed on a 30 setting shaft 42, the latter being journaled in bearings 43 and 44 in the opposite ends of the main frame, this setting shaft being provided with a knob 45, or equivalent means, on the exterior of the casing of the machine, 35 by which the shaft, and in consequence the screw 41, may be rotated, as a result of which the body 35 which carries the punch and its cooperating die will be shifted longitudinally along the bar 40. In this way, the 40 punch may be brought into a position to punch any one of the several longitudinally divided spaces on the ticket after the latter has been brought into cooperative relation with the punching device. In order to indicate the different settings of the punching device to show to the ticket purchaser how the ticket is to be punched and also to aid the operator of the machine in setting it to 45 punch the selected space in the ticket, an indicator is provided which is set concurrently with the setting of the punching device. This indicator in the present instance comprises a rotatable dial 46 which is fixed to a shaft 47, the latter being journaled in a 50 suitable bearing bracket 48, and the dial shaft 47 is connected by gearing 49 to a shaft 50, the latter being journaled toward one end in the bracket 48 and at its opposite end in a bearing 51 on the main frame, 55 and this shaft 50 is connected by gearing 52 to the setting shaft 42. Reduction gearing is preferably used between the shafts 42 and 50 in order that the setting shaft may have a range of adjustment which includes 60 a suitable number of revolutions of the setting shaft, although the complete range of movement of the dial may be comprised within one revolution thereof. The periphery of the dial bears one or more sets of numerals, or other characters corresponding to the several spaces on the ticket, and these numerals or characters are so arranged that the proper character will show through a suitable opening in the casing when the 65 punching device is set to punch the corresponding space in the ticket. For example, in the present instance, a sight opening 53 may be provided in the front of the casing of the machine through which the different numerals or characters on the lower portion of the dial may be observed, and another wall of the casing may have a sight opening 54 therein, through which any one of the numerals or characters of the upper set of the dial may be used, the latter sight opening being used by the operator of the machine as an aid in setting the machine to 70 punch a selected space on the ticket. Means is provided for actuating the punch at any position in which it may be set along the bar 40. Preferably and as shown, the punch actuating means comprises a bar 55 which extends longitudinally above the bar 40 and immediately above the path of the stem 39 of the punch so that this stem of the punch will occupy a position immediately below the bar 55, irrespective of the position along the bar 40 at which the punch may be set. This actuating bar 55 is fixed at its ends to radial arms 56, the latter in turn being fixed to a rock shaft 57. This rock shaft is journaled at its ends in the brackets 43 and 48 and it is provided with an actuating arm 58 which is connected by a link 59 to a lever 60, the latter being pivoted on a pivot pin 61 which is relatively fixed. The lever 60 is provided with a roller or projection 62 which rides upon a cam 63 fixed on the operating shaft 29, the roller 62 being held in engagement with the cam by a tension spring 64 which acts to pull down the link 59. This spring likewise serves to restore the punch actuating bar 55 to its normally elevated position and to hold it in such position after each actuation 75 of the punch. The punch actuating cam 63 is so set on the operating shaft 29 that the continued rotation of the operating shaft, after the Geneva movement has advanced the ticket strip to position another ticket for punching this cam will act on the roller 62 to swing the lever 60 upwardly, thereby pushing upwardly the link 59 and rocking the shaft 57 in a direction to depress the bar 55, the latter bearing down upon the stem 39 of the punch, and thus forcing the punch 80 downwardly through the space of the ticket registering therewith, thus providing the ticket with a perforation which designates the point of issue of the ticket, as represent- 85 90 95 100 105 110 115 120 125 130

ed by the space in which the punch mark is made. The continued rotation of the operating shaft carries the punch actuating cam 63 beyond the roller 62, and the spring 64 acts to restore the parts to the normal position shown by the full lines in Figure 3, the bar 55 being then held in its elevated position and clear of the punch actuating stem 39 so that the latter may, if desired, 10 be shifted to a different position beneath this bar.

The severing device which separates the punched or marked ticket from the remainder of the ticket strip comprises preferably 15 a stationary shear or knife member 65 which is located imminently above the path of the ticket strip and against the underside of which the ticket strip is adapted to bear, and a movable knife or shear member 66, 20 that shown being pivoted at 67 to the upper stationary shear 65 and having its cutting edge arranged to cooperate with the stationary shear member to cut the foremost ticket from the remainder of the ticket strip. The 25 movable knife member 66 is preferably operated at the proper moment from the operating shaft 29, it being operatively connected by a link 68 to a lever 69, the latter being pivoted on a stationary pin 70 and carrying a roller or projection 71 adapted to ride upon the shear operating cam 72, this cam being fixed on the operating shaft 29. A spring 73 acts to hold the roller or projection 71 in engagement with the shear actuating cam and this spring also serves to 30 return the movable knife 66 to its normal inactive position, as shown by the full lines in Figure 3. The shear actuating cam 72 is so set on the operating shaft 29 that the 35 shear is operated to sever a ticket after such ticket has been punched and the ticket strip has been advanced to project the punched ticket through the slot 12 and to bring another ticket forward into position for punching.

In order to insure accurate punching of each ticket and particularly to avoid punching a ticket so that the punch mark will be partly in one space on the ticket and partly 50 in another adjacent space thereon, means is preferably used to restrain the machine from operation unless the machine has been properly set to correctly punch the ticket. Such means consists preferably of a controlling disk 74 which is fixed on the setting shaft 42 and is formed with notches 75 with which a dog 76 may cooperate under the action of a spring 77, the notches 75 being so located that each time the dog 76 engages 55 one of these notches, the punch will be correctly set to accurately punch a corresponding space on the ticket. The dog 76 serves to yieldingly hold the shaft 42 in its different set positions, although the dog 76 will 60 be displaced from the notch which it en-

gages when sufficient force is applied to the knob 45 to turn this shaft. A lever 78 is pivoted at 79 to a stationary part of the machine and is provided with a locking dog 80 which, when the shaft 42 occupies a correct position for the operation of the punch relatively to the different spaces on the disk, will swing into a notch 75 in the disk 74, but if the setting shaft 42 has not been brought fully into a position to properly set the punch, the dog 80 will not enter the notch in the disk 74, but will strike upon a portion of the periphery of the disk, thus preventing a complete swing or movement of the lever 78. This lever 78 is provided 75 with a spring 81 which normally acts to retract the dog 80 relatively to the disk 74. The operating shaft 29 has a disk or other suitable member 82 fixed thereon and this disk is provided with a shoulder 83 which is arranged to strike a stop 84 on the lever 78 when the operating shaft 29 has completed an operation, it being understood that the shaft 29 is revolved in a clockwise direction, as shown in Figure 5, to effect an operation of the machine. The engagement of the shoulder 83 on the disk 82 with the stop 84 on the lever 78 will thus lock the machine from operation until the lever 78 is swung through an angle sufficient to remove the stop 84 thereon from the path of movement of the shoulder 83. Unlocking is effected preferably by a projection 85 which is fixed to the disk 82 and is arranged in the path of a finger 86 formed on a ratchet 87, the latter being pivoted at 88 on the lever 78 and normally held in the path of the projection 85 by a spring 89, a stop 90 on the lever 78 limiting the movement of the latch under the influence of the spring 89. By this arrangement a reverse or anticlockwise rotation of the operating shaft (Figure 5) as a preliminary to the actuating or clockwise rotation of this shaft, will cause the projection 85 on the disk 82 to move to the right in Figure 5, thus bringing it against the end of the finger 86, and the latter, being attached to the lever 78, will cause said lever to swing in a direction to force the dog 80 thereon into a properly located notch 75 in the disk 74. If the shaft 42 has been properly set, one of the notches 75 in the disk 74 will register with the dog 80 and the latter may therefore enter the notch sufficiently to enable the stop 84 on the lever 78 to be swung clear of the path of the tooth or shoulder 83 on the disk 82, and when the lever 78 has been swung or displaced to this extent, a retaining latch 91, which is pivoted at 92 to a relatively fixed part of the frame, will operate under the action of its spring 93 to engage a tooth 94 thereon with a notch 95 formed in the peripheral portion of the lever 78, whereby the latter will be held in its 130

unlocked position, the stop 84 being clear of the tooth or shoulder 83 of the disk 82, while the dog 80 is locked in a notch 75 in the disk 74. The shaft 29 may then be 5 rotated in a forward direction through a complete revolution which will perform a complete cycle of operations within the machine, and the final part of this revolution of the shaft 29 will cause a pin 96, which 10 projects from one side of the disk 82, to ride upon a beveled part 97 of the latch 91, thus pushing the tooth 94 on the latch out of engagement with the notch 95 in the lever 78, and the latter acting under the influence 15 of its spring 81 will restore the lever 78 to its normal position, with the stop 84 thereon in the path of the tooth or shoulder 83, on the disk 82, the engagement of the tooth or shoulder 83 with the stop 84 arresting the 20 rotation of the operating shaft 29 at the completion of a single revolution thereof. Thus, after the machine has been properly set to punch a ticket, it may be unlocked and operated to effect such punching, but 25 while the machine is being operated to punch the ticket, the punch setting means is locked against any change until after the selected punching has been completed, and furthermore only one ticket can be punched 30 and issued at each operation of the machine. If it should happen that the shaft 42 has not been set correctly to effect a selected punching, the dog 80, when the frame 78 is displaced by preliminary reverse rotation 35 of the shaft 29, will strike a portion of the periphery of the disk 74, thus preventing a complete movement of the frame 78. The tooth 94 on the latch 91 will not engage the notch 95, and hence the stop 84 on the lever 40 78 will not be held out of the path of the tooth or shoulder 83 on the disk 82. Rotation of the shaft 29 in a forward direction to effect the operation of the machine, will then be prevented until the shaft 42 has been 45 properly set.

The mode of operation of the machine may be described briefly as follows: The 50 punch or marking device is brought into the proper position to correctly punch or mark the selected space or portion of the ticket by rotating the knob or handle 45 in the proper direction until the numeral or character on the dial, visible through the sight opening, corresponds with the space or portion 55 of the ticket which is to be punched or marked. With the machine set to punch or mark the ticket in the selected manner, the crank 31 is partially revolved first in a reverse direction, which serves to unlock this 60 crank for forward rotation and to lock the setting means to prevent any change in the setting of the punch during the punching operation. The crank 31 is then rotated through a full revolution and returned substantially 65 to its initial position. The first

part of this forward revolution of the crank causes the cam 63 to actuate the punch to perforate or mark in an equivalent way, the selected space or portion of the ticket; the continued rotation of the crank in a forward 70 direction causes the Geneva movement to actuate the feed mechanism to advance the ticket strip through a predetermined and definite advance which will project the marked ticket through the slot 12 and will 75 bring the next ticket on the strip into co-operative relation with the punching device so that the different mark receiving spaces on this ticket will correspond accurately 80 with the different positions in which the punching device may be set. The final portion of the forward rotation of the crank 31 brings the cam 72 into operation whereby the knife blade 66 is actuated to sever the punched ticket from the ticket strip, the punched ticket being thereby delivered upon the chute or shelf. The operation of the handle 31 is arrested by the stop 84 on the lever 78 which returns to a position in front of the shoulder 83 on the disk 82, the lever 78 being tripped during the final portion of the rotation of the shaft 29, by the pin 96, which releases the tooth 94 of the latch 91 90 from the notch 95 in the lever 78, so that one ticket only may be issued at each operation 95 of the machine. When the cycle of operations has been completed, the machine is in condition for similar subsequent operation and the next ticket may be issued either without changing the setting of the punching and marking device or after the setting has been changed, as may be required.

While a punching device is herein shown and described as the means for marking the selected designating space of the ticket or equivalent device, it will be understood that other forms of marking means may be used, although punching means is preferably used for this purpose because of the advantages which it possesses over other types of marking devices.

Means may be provided, as shown in Figures 1 and 8 for feeding the last ticket or tickets of the strip from the machine, such means preferably comprising a roller 100 which is fixed to a shaft 101 and is arranged and adapted to frictionally bear upon the portion of the ticket strip resting on the guide plate 34. One end of the shaft 101 projects through one side of the machine to the exterior thereof and is provided with a knurled head or other suitable operating part 102 which may be manipulated manually by the operator of the machine to advance the final portion of the ticket strip 110 after the same has passed beyond the main feed roller 7.

I claim as my invention:—

1. In a machine for marking tickets, the combination of means for feeding a ticket 120

- strip longitudinally to position a ticket having a series of spaces thereon any one of which may receive a designating mark, and a marking device common to all the spaces on the ticket, the marking device and ticket being relatively movable in a direction longitudinally of the strip to cause registration between the marking device and any selected space on the ticket.
- 5 2. In a machine for marking tickets, the combination of means for feeding a ticket strip longitudinally to position a ticket having a row of spaces arranged longitudinally thereon, and a marking device capable of marking any one of the spaces of a ticket, the marking device and ticket being relatively movable in a direction longitudinally of the ticket strip to bring the marking device into registration with any selected space on the ticket.
- 10 3. In a machine for marking tickets, the combination of means for feeding a ticket strip longitudinally to position a ticket having a series of spaces arranged longitudinally thereon, a single marking device shiftable relatively in a direction longitudinally of said series of spaces and the ticket strip to bring the marking device into registration with any selected space of the series, and means for setting the marking device to register it with any selected space on the ticket.
- 15 4. In a machine for marking tickets each having a row of designating spaces arranged longitudinally thereon, the combination of means for advancing such a ticket longitudinally to bring it into a predetermined position, and a marking device shiftable longitudinally of the ticket so positioned to bring it into registration with any selected designating space thereon.
- 20 5. In a machine for marking tickets each having a row of designating spaces arranged longitudinally thereon, the combination of means for advancing such ticket and for holding it in a relatively fixed predetermined position, a marking device shiftable longitudinally of the ticket to bring it into registration with any selected designating space thereon, and a non-shiftable actuator for the marking device which maintains operative relation with the marking device throughout the range of shifting movement of the latter.
- 25 6. In a machine for marking tickets each having a series of designating spaces thereon, the combination of means for positioning such a ticket, marking means, the latter and the ticket being relatively movable to bring the marking means into registration with a selected designating space of the ticket, means for actuating the marking means, and means controlled by the setting of the marking means relatively to the ticket for restraining operation of the actuating
- means unless the marking means is set relatively to the ticket to correctly mark the selected designating space thereof.
7. In a machine for marking a ticket having a plurality of designating spaces thereon, the combination of means for positioning a ticket, a single marking device capable of marking any one of the spaces on the ticket, a member operative to shift said device relatively to the ticket to bring it into a position to mark a selected designating space on the ticket, means for actuating the marking device, and controlling means governed by said member to prevent actuation of the marking device except when the latter is set to correctly mark the selected designating space on the ticket.
- 75 8. In a marking device, the combination of means for positioning a ticket to be marked, a marker shiftable relatively to the ticket into different positions to bring it into registration with any one of a plurality of parts of the ticket to be marked and a non-shiftable actuator which is elongated in the direction of shift of the marker to remain in actuating relation therewith throughout the range of shifting movement of the marker.
9. In a ticket punching machine, the combination of means for positioning a ticket having a plurality of designating spaces thereon, a punch shiftable into different positions to bring it into registration with any selected space on such ticket, and an actuator comprising a bar extending in the direction of shift of the punch to remain in actuating relation therewith throughout its range of shifting movement and reciprocatory to actuate the punch.
- 95 10. In a machine for marking a ticket having a longitudinal row of designating spaces, the combination of means cooperative with one longitudinal edge of the ticket to support it, and a marking device movable along and supporting the opposite longitudinal edge of the ticket and adapted to assume different positions longitudinally of the ticket and in registration with any selected designating space on the ticket.
- 100 11. In a machine for marking a ticket having a row of designating spaces, the combination of means for positioning such ticket, a punch capable of punching any one of such spaces, a guide bar along which said punch is slidable to bring it into registration with any selected space on the ticket, and a screw arranged parallel to said guide bar and cooperative with the punch to shift the latter.
- 115 12. In a machine for marking and issuing tickets from a ticket strip, each ticket having a row of designating spaces thereon, means shiftable longitudinally of such row of spaces and operative on such ticket to mark any selected designating space there-

on means operative subsequently to advance the ticket in a direction longitudinally of its row of designating spaces and to bring another ticket into predetermined position, 5 and means operative finally to sever the marked and advanced ticket from the remainder of the ticket strip.

In testimony whereof I have hereunto set my hand in presence of two subscribing witnesses.

CARL O. FEDDERN.
